[57] **CLAIM**

The ornamental design for a combined comb for applying hair gel and cover therefor, as shown and described.

DESCRIPTION

FIG. 1 is a top perspective view of a combined comb for applying hair gel and cover therefor showing our new design;

FIG. 2 is a front elevational view thereof, the rear elevational view being identical in appearance;

FIG. 3 is a side elevational view thereof, the side opposite being identical in appearance;

FIG. 4 is a top plan view thereof;

FIG. 5 is a bottom plan view thereof;

FIG. 6 is an exploded perspective view showing the comb and cover portions in a separated positioning spaced from each other; and,

FIG. 7 is a front elevational view of the comb shown without the cover for clarity of illustration.
